METHOD OF MAKING COILED SPRINGS AND SPRING CASINGS

Application filed April 18, 1922. Serial No. 555,412.

This invention relates to a new method of winding coiled springs, casings, and the like, eliminating the usual heat treatment which has up to this time been found necessary in order to produce a spring or casing of the type referred to having the several coils or convolutions thereof closed or in actual contactual relation to each other.

The invention is particularly adapted to 10 flexible casings such as are used in conjunction with an enclosed flexible cable similar to what is known as the Bowden wire control. A casing produced by the method hereinafter particularly described is superior to the ordinary flexible tubular casing in that when the cable and casing are performing their respective functions the casing is under actual compression while the cable or enclosed wire is under tension.

20 With the above and other objects in view, the invention consists in the novel method herein fully described and claimed.

The accompanying drawing represents a coiled spring or casing, diagrammatically illustrating the novel method involved.

In the drawing, 1 designates a coiled spring, casing or the like, and 2 designates the rod or wire from which the spring or casing is formed.

30 In the preferred manner of carrying out the invention, the rod or wire 2 is wound upon a standard spring arbor, in the same manner the springs are now wound. As the arbor is turned the wire to be coiled is drawn 35 from a source of supply, and the straight incoming part *c* is continually forced laterally by the formed portion of the work in the direction indicated by arrow *d*. The lateral movement of the part *c* tends to set up an 40 axial twist in its adjacent coiled part, indicated as a section of the coil lying between dotted lines *a* and *b*. This is what may be termed the normal twist of a coiled wire. In 45 this illustration the normal twist is counterclockwise. To overcome this twist and to cause the adjacent convolutions of the formed coil to forcibly hug each other, the part *c* of the wire is given an axial twist in a clockwise direction, as indicated by the full line 50 arrow in the drawing, such axial twist being

given to the wire or rod simultaneously with the winding of the rod or wire around the arbor. This axial twist of the rod or wire 2 causes a natural tendency of the metal, which has been stressed an amount not to exceed the elastic limit of the metal, to untwist in the direction of the dotted arrow in the drawing, to assume its original condition so that each convolution hugs the next convolution. In other words, where the rod or 55 wire 2 is wound onto an arbor and twisted in the direction of the full line arrow in the drawing, each coil of the wire as it is coiled onto the arbor untwists slightly in the direction of the dotted arrow in the drawing, and 60 in so doing moves into close relation with the next coil. This is a simple mechanical process. The twisting can't obviously exceed the elastic limit of the wire, or there will be no 65 tendency for the wire to go back to the original untwisted condition. It is likewise apparent that the extent to which the twisting is carried determines the extent to which the wire will untwist, and hence determines the recoiling characteristics, that is, lack of 70 flabbiness of the completed spring or spring casing. As a result of the operation and method hereinabove described, the convolutions of the spring or casing are forced into 75 close contactual relation to each other resulting in a spring or casing which is always under compression and which is nevertheless flexible. The spring casing snaps back or recoils when flexed and is not flabby as are 80 springs or spring casings wound without the 85 twist mentioned. This is a very desirable characteristic for use in Bowden casings. It will be observed that the result above described is obtained without the heat treatment heretofore found necessary in securing 90 practical results. The improved product is superior to the old product due to the elimination of end play of the casing or easy separation between the convolutions thereof and furthermore the cost of production is materially reduced.

Instead of winding the wire or rod around a mandrel it may be forcibly fed into a tubular die with an internal spiral or thread-like channel which the convolutions will readily 100

follow. The wire or rod is twisted just before it enters such die.

Having thus described my invention, I claim:

- 5 1. In the art of making coiled springs, the herein described method, consisting in winding a rod or wire into a coil and simultaneously causing the convolutions of the coil to assume a closed contactual relation by im-
10 parting an axial twist to the rod or wire.
- 15 2. In the art of making coiled springs, the herein described method, consisting in winding a rod or wire into a coil and simultaneously causing the convolutions of the coil to
15 assume a closed contactual relation by impart-
ing an axial twist to the rod or wire in one direction so it tends to untwist in the other direction and in so doing causes each convolution to hug the next adjacent convolution.
- 20 3. In the art of making coiled springs, the herein described method, consisting in winding a rod or wire and simultaneously impart-
ing an axial twist to the rod or wire to an extent within the elastic limits of the rod or
25 wire to produce a close-wound spring with the convolutions in contactual relation.
- 30 4. The process of making a coil by twisting a rod or wire an amount not to exceed the elastic limit thereof and in the direction oppo-
site to the normal twist of the rod or wire.

In testimony whereof we have affixed our signatures.

CHARLES LEIGH PAULUS.
HERBERT O. RUSSELL.
